UNITED STATES PATENT OFFICE.

WILLIAM A. SALTER, OF KANSAS CITY, MISSOURI, ASSIGNOR, BY MESNE ASSIGNMENTS, TO E. H. PURDY, OF CLAY CENTER, KANSAS.

GEARING.

1,137,026.

Specification of Letters Patent. Patented Apr. 27, 1915.

Application filed May 9, 1911. Serial No. 626,590.

To all whom it may concern:

Be it known that I, WILLIAM A. SALTER, a citizen of the United States, residing at Kansas City, in the county of Jackson and State of Missouri, have invented certain new and useful Improvements in Gearing, of which the following is a specification.

This invention relates to gearing for renovators of that class whereby fabrics are cleaned within a drum rotated through a body of gasoline or analogous liquid, and my object is to produce a machine of this character whereby fabrics may be quickly and efficiently cleaned and dried, my special object being the provision of means for automatically rotating the drum in reverse directions alternately to effect the thorough cleansing of fabrics within the drum and for rotating the latter in a single direction at high speed to expeditiously dry such fabrics.

A further object is to produce a machine of this character of simple, strong, durable and inexpensive construction.

With these and other objects in view as hereinafter appear, the invention consists in certain novel and peculiar features of construction and organization as hereinafter described and claimed; and in order that it may be fully understood reference is to be had to the accompanying drawings, in which—

Figure 1, is a side view of a renovator embodying my invention. Fig. 2, is a plan view of a part of the machine. Fig. 3, is a vertical section on the line III—III of Fig. 2, and Fig. 4 is a fragmentary view showing the hinge relation between two of the doors.

In the said drawings—1 indicates a supporting end frame, there being one of these frames at each side of the machine, and mounted upon and secured to said frames is a gasoline receptacle consisting of vertical semi-circular sides 2, and a semi-cylindrical body 3, between the sides, and said body is provided at its rear upper edge with a downwardly and inwardly opening hook or stop 4. Underlying the body 3 of the receptacle 5 is a receptacle for hot water, provided

at its front side with a short tube 6 for convenience in introducing the water into said receptacle 5 and provided with a drain tube 7 equipped with a spout 8, controlled by a valve 9.

10 is a tube through which gasoline may be withdrawn from the gasoline receptacle, said tube preferably extending down through the receptacle 5 and thence through the adjacent end frame 1, and outward of the latter it is provided with a controlling valve 11.

12 indicates a semicylindrical hood or cover of smaller diameter than the gasoline receptacle, so as to be capable of swinging within the latter, said hood being provided at its rear edge with an upturned outwardly-disposed hook or stop 13, for engagement with the hook or stop 4, and at its front end with a cleat 14 as a filling strip between it and the inner surface of the body 3 of the gasoline receptacle. The said filling strip, when the hood is opened, provides a convenient handle whereby latter can be readily closed, as shown in Figs. 2 and 3.

Arranged concentrically within the gasoline receptacle and its hood or cover 12, is a cylindrical drum, consisting preferably of imperforate ends 15, and a perforated body composed of segmental doors 16, the adjacent ends of the doors overlapping and being supported by parallel bars 17 connecting the ends 15, as shown clearly in Fig. 3.

In practice, each door is provided with a plurality of hinge loops 18. Near each edge, and engaging the adjacent hinge loops of juxtaposed doors are slidable hinge rods 19, each rod being of substantially step form with one of the steps engaging certain of the hinge loops of the doors. The rods are also provided with return bend portions or arms 20 which engage the remaining loops of the doors. By this arrangement it will be seen that the doors are reliably connected together with a hinged relation and that the unengaged step of the rod can be conveniently utilized as a handle for sliding it endwise and disengaging it from the loops of one of the doors to permit such door to

be opened. By similarly withdrawing the rod at the opposite side of said door, the latter can be detached from the drum. By this arrangement it will be seen that one or 5 all of the doors may be opened—without disturbing the others or any part of the machine—to facilitate the cleaning of the latter. The drum is provided with trunnions 10 projecting outwardly from its ends, and 10 said trunnions are journaled in the ends of the semicylindrical receptacle, it being noted in this connection that the ends of the hood or cover are journaled on the trunnions between the ends of the drum and the ends 15 of the semicylindrical receptacle in order that the said hood or cover may be caused to swing into the said receptacle below the drum and thus expose and give access to the upper half of the latter.

20 22 is a horizontal stub-shaft projecting outwardly from one end of the semicylindrical receptacle, and journaled thereon is a wheel 23, adapted to be driven by a belt, not shown, if desired, and said wheel is also 25 provided with a handle 24 for convenience in manually operating the machine. Rotatable with wheel 23 is a gear pinion 25, meshing with a gear wheel 26 journaled on a second but shorter horizontal stub shaft 27 projecting from the same end of the said 30 receptacle, and rotatable with said wheel 26 is a small pinion 28, meshing with a large gear wheel 29 journaled on a third stub-shaft 30, projecting from said receptacle.

35 Wheel 29 is also provided with a wrist pin 31, with which a pitman 32 is pivotally connected and said pitman is provided with an offset longitudinal portion 33, provided with a longitudinal slot 34, slidably receiving a 40 hollow shaft 35, journaled on a fourth stub-shaft 36 projecting from said receptacle, and for convenience in turning said hollow shaft 35 by hand, it is equipped with a crank handle 37.

45 At the outer end of the offset portion 33 of the pitman is a lug 38, provided with a slot 39, and adapted to engage said slot when the cleaning operation of the machine is in progress, is a clamping screw 40, carried at one end of a rack-bar 41 pivotally connected at its opposite end at 42, to the pitman, the clamping screw by binding at its headed end on lug 38 securing the rack-bar rigidly in position and in engagement 50 with a gear wheel 43 rigidly secured on the hollow shaft 35. Rigidly secured on the same shaft is a large gear wheel 44 meshing with a small gear wheel 45 rigidly secured on the adjacent trunnion of the drum. By 55 this arrangement it will be seen that rotation imparted to wheel 23 is transmitted through the connections described to the drum and that through the reciprocating action of the rack bar, the rotation of the

drum is automatically reversed without affecting the continuous rotation in one direction of wheels 23, 25, 26, 28 and 29, the remaining wheels of course rotating forward and backward alternately to impart corresponding movement to the drum.

70 When it is desired to rotate the drum continuously in one direction, the clamping screw 40 is turned backward to permit of upward adjustment of the rack bar until it is disengaged from wheel 43 and then the 75 movement of the screw is reversed to clamp the rack bar in its disengaged or inoperative position. The handle 37 is then turned to impart rotation at a high rate of speed, to the drum.

80 In practice the clothes are placed in the drum and submerged in gasoline contained within the gasoline receptacle. Hot water is then introduced into the receptacle 5 for the purpose of heating the gasoline without 85 danger of explosion. The wheel 23 is then revolved and as a result of such action the drum is first revolved in one direction and then in the other for the purpose of subjecting the clothes to more or less forcible contact with the gasoline through the violent 90 agitation thereof due to such movement of the clothes. After the lapse of twenty or thirty minutes, the clothes are thoroughly cleaned and the gasoline is drawn off by 95 opening the valve or stop cock 11. The rack bar is then withdrawn from engagement with the wheel 43 as hereinbefore explained and secured in its inoperative position, this adjustment being followed by the rotation 100 of shaft 35 through the instrumentality of handle 37, the wheels 43, 44 and 45 transmitting such power for the purpose of revolving the drum at high velocity. Under 105 this high speed of the drum in one direction what little gasoline remains in the clothes is extracted by centrifugal force and within a few minutes every vestige is driven out of the clothes and the latter are taken out of the machine ready for the dry room or 110 sunlight, in a thoroughly cleansed condition.

115 From the above description it will be apparent that I have produced a renovator embodying the features of advantage enumerated as desirable in the statement of the object of the invention and I wish it to be understood that while I have illustrated and described the preferred embodiment of the invention I do not desire to be restricted to the exact details of construction shown and 120 described as obvious modifications will suggest themselves to one skilled in the art.

I claim:

125 The combination with a wheel and means for driving it, of a rotatable element, a wheel geared thereto, a pitman pivoted to the first-named wheel and guided with respect to the last-named wheel, and a rack

bar engaging the last-named wheel and carried by the pitman, the rack-bar being adjustable to withdraw it from engagement with said wheel, and means whereby 5 said wheel may be rotated continuously in one direction when not engaged by the rack-bar.

In testimony whereof I affix my signature, in the presence of two witnesses.

WILLIAM A. SALTER.
